Fig. 9.

FIGURE 1 is a side elevational view of a luminaire showing my new design wherein the rear of the housing has a projecting pole support member;

FIG. 2 is a top plan view of the luminaire of FIG. 1; FIG. 3 is a front elevational view of the luminaire of FIG. 1;

FIG. 4 is a rear elevational view of the luminaire of FIG. 1;

FIG. 5 is an enlarged vertical sectional view of the luminaire shown in FIG. 1 taken substantially along the center thereof;

FIG. 6 is a side elevational view of a modified form of the luminaire shown in FIG. 1 wherein the rear of the housing is substantially flat;

FIG. 7 is a top plan view thereof as shown in FIG. 6;

FIG. 8 is a front elevational view thereof as shown in FIG. 6 with the lens omitted for convenience of illustration; and

FIG. 9 is a rear elevational view of the luminaire of FIG. 6.

The dominant features of my design reside in the portions shown in full lines with the bracket and fragmentary pole disclosed in FIGS. 1 and 6 and the light bulb shown in FIG. 5, for illustrative purposes only.

I claim:

The ornamental design for a luminaire, substantially as shown and described.
